INVENTOR

Joseph Bardsley

UNITED STATES PATENT OFFICE.

JOSEPH BARDSLEY, OF NEWARK, NEW JERSEY.

DOOR-KNOB.

SPECIFICATION forming part of Letters Patent No. 314,644, dated March 31, 1885.

Application filed December 29, 1884. (No model.)

To all whom it may concern:

Be it known that I, JOSEPH BARDSLEY, a citizen of the United States, and a resident of Newark, in the county of Essex and State of New Jersey, have invented certain new and useful Improvements in Door-Knobs, of which the following is a specification.

The invention relates to improvements in door-knobs; and it consists in novel methods 10 of manufacture, as hereinafter described, and particularly pointed out in the claim. In Letters Patent of the United States No. 301,850, granted to me July 15, 1884, I have described and claimed a door-knob in the shank of which 15 is a metallic sleeve, the sleeve being inserted into the shank and afterward threaded, whereby it is effectually held in place and adapted to receive the threaded end of a knob-spindle, and in said patent I reserved the right to make 20 the method of manufacturing and securing the metal sleeve in the knob-shank the subject of a separate application for protection, the said patent being limited to the article, and the 25 present application being presented for the purpose of covering the method of manufacture.

Referring to the accompanying drawings, Figure 1 is a central vertical longitudinal section of a pair of knobs embodying the elements 30 of the invention. Fig. 2 is a vertical transverse section on the line x x of Fig. 1. Fig. 3 is a view of the sleeve prior to its insertion in the knob-shank. Fig. 4 is a central vertical longitudinal section of a door-knob, showing 35 the formation of the knob-shank lining when a comparatively thick metal tube is used for same.

In the drawings, A denotes the door; B C, respectively, the knobs, and D the spindle, 40 which passes through a suitable aperture in the door and receives upon its ends the knobs. The knobs B C will preferably be of wood, and each will be provided with a suitable shank, E, within which is cut a socket, F, of 45 suitable form and dimensions to snugly receive the metallic sleeve G prior to its being threaded. The sleeve G will preferably be provided with a longitudinal rib, H, which will enter a corresponding groove in the socket 50 F, and prevent the sleeve from turning dur-

ing the process of threading, as hereinafter described, and while the knob is in use. After the sleeve G has been inserted into the socket F, it will be threaded by a suitable tool screwed therein, when it will be ready for insertion 55 upon the ends of the threaded spindle D, where the knob will be retained by a screw, I, or other suitable device.

Heretofore in manufacturing wooden door-knobs great difficulty has been experienced in 60 securing a metallic sleeve in the knob-shank without making the latter unduly large and cumbersome or incurring great expense in the manufacture. The object of the present invention is to produce a method whereby a metal- 65 lie sleeve may be effectually secured in the knob-shank in a rapid inexpensive manner, and without destroying the attractive appearance of the lock. The method of manufacture herein described, which consists in first insert- 70 ing the sleeve in the socket of the knob-shank and then threading it, is advantageous in many respects, among which may be mentioned the fact that it permits of the use of a longitudinal rib on a threaded sleeve, and that the opera- 75 tion of threading the sleeve after its insertion into the knob-shank has the effect of expanding its sides against the walls of the socket re- 80 ceiving it, whereby the sleeve will be firmly held in place, and will be rendered more durable and effectual on account of its close contact with the walls of the socket in the knob-shank. The exterior surface of the sleeve G will be more or less expanded into a thread by the 85 operation of threading the interior portion thereof, according to the thickness and character of the metal employed, and at any rate the formation of the interior thread will expand the sleeve, so that it tightly impinges the walls of its socket. Fig. 4 shows the character 90 of the threads formed when a thick metal tube is used for the lining of the knob-shank. The tube shown is expanded and a slight exterior thread formed, and it is firmly secured in place.

Cast-iron sleeves have heretofore been in- 95 serted in knob-shanks; but these have been threaded prior to their insertion. The opera- 100 tion of threading has not assisted in securing the sleeve, and the sleeve has had no longi- tudinal rib.

It will be obvious that when thin metal is used for the sleeve G the rib H may be formed after the sleeve has been inserted into the knob-shank by simply driving a ribbed tool into it, 5 and in this case the rib will be pressed into the wood, and operate to prevent the sleeve from turning in its socket when the knob is in use. This method of manufacture may be followed, if desired; or when thick metal is used for the 10 sleeve the rib and thread may be formed on it prior to its insertion into the knob-shank. I do not, therefore, limit my invention to any particular order of following the steps of the invention; but 15 What I claim as new, and desire to secure by Letters Patent, is—

In the manufacture of door-knobs, the method of lining the knob-shank with metal, which comprises the following steps: giving the metal tube a longitudinal rib, inserting it 20 into the knob-shank, and threading it to receive the knob-spindle, substantially as set forth.

Signed at New York, in the county of New York and State of New York, this 22d day of December, A. D. 1884.

JOSEPH BARDSLEY.
